United States Patent Office

Des. 185,228
Patented May 19, 1959

185,228

TEXTILE FABRIC OR SIMILAR ARTICLE

Thomas W. Nelson, Boston, Mass., assignor to American Twine & Fabric Corporation, Boston, Mass., a corporation of New Hampshire

Application December 23, 1958, Serial No. 53,886

Term of patent 14 years

(Cl. D92—1)

The single figure is a plan view of a textile fabric or similar article showing my new design.

I claim:

The ornamental design for a textile fabric or similar article, substantially as shown.

References Cited in the file of this patent

UNITED STATES PATENTS

D. 75,660	Sheft -----	June 26, 1928
D. 90,395	Christen -----	Aug. 1, 1933
D. 156,185	Vogel -----	Nov. 22, 1949